US00D949989S

(12) **United States Design Patent** (10) **Patent No.:** **US D949,989 S**
(45) **Date of Patent:** **** Apr. 26, 2022**

(54) **ATTACHMENT POST**

(71) Applicant: **Coulter Ventures, LLC.**, Columbus, OH (US)
(72) Inventors: **Ahmik Jones**, Upper Arlington, OH (US); **William Henniger**, Columbus, OH (US); **Emmanuel Sergakis**, Plain City, OH (US)

(73) Assignee: **Coulter Ventures, LLC.**, Columbus, OH (US)

(**) Term: **15 Years**

(21) Appl. No.: **29/744,118**

(22) Filed: **Jul. 27, 2020**

Related U.S. Application Data

(63) Continuation of application No. 29/667,364, filed on Oct. 19, 2018, now Pat. No. Des. 891,545.

CLAIM

The ornamental design for an attachment post, as shown and described.

DESCRIPTION

FIG. 1 is a top, front, right perspective view of an attachment post showing our new design;
FIG. 2 is a right side view thereof;
FIG. 3 is a left side view thereof;
FIG. 4 is a bottom view thereof;
FIG. 5 is a top view thereof;
FIG. 6 is a front view thereof;
FIG. 7 is a rear view thereof; and,
FIG. 8 is a perspective view of an attachment post shown in a condition of use thereof.

The broken lines shown in the drawings are for the purpose of illustrating portions of the attachment post which form no part of the claimed design. The additional broken lines in FIG. 8 are for the purpose of showing environmental structure, which form no part of the claimed design.

1 Claim, 5 Drawing Sheets
